Attn:

UNITED STATES PATENT OFFICE.

ERNEST T. BECK, OF MERIDEN, CONNECTICUT, ASSIGNOR TO INTERNATIONAL SILVER CO., OF MERIDEN, CONNECTICUT, A CORPORATION OF NEW JERSEY.

DESIGN FOR A METAL BOWL OR SIMILAR ARTICLE.

Application filed November 9, 1927. Serial No. 24,051. Term of patent 7 years.

To all whom it may concern:

Be it known that I, ERNEST T. BECK, a citizen of Germany, residing at Meriden, in the county of New Haven and State of Connecticut, have invented a new, original, and ornamental Design for a Metal Bowl or Similar Article, of which the following is a specification, reference being had to the accompanying drawing, forming part thereof.

Fig. 1 is a side view of a metal bowl showing my new design;

Fig. 2 is an end view of the same; and

Fig. 3 is a top view of the same.

I claim:

The ornamental design for a metal bowl or similar article as shown.

ERNEST T. BECK.
